CONVERSION OF HYDROCARBONS

George B. Arnold, Beacon, N. Y., assignor, by
mesne assignments, to The Texas Company,
New York, N. Y., a corporation of Delaware

Application October 9, 1941, Serial No. 414,253

5 Claims. (Cl. 196—13)

This invention relates to the conversion of hydrocarbons and has to do with the isomerization of hydrocarbons to form branched chain hydrocarbons. It is applicable to the isomerization of naphtha hydrocarbons.

The invention contemplates the treatment of naphtha hydrocarbon mixtures containing aromatic and non-aromatic hydrocarbons to selectively remove aromatic hydrocarbon constituents therefrom and subject the hydrocarbons from which aromatic constituents have been removed to isomerization for the production of gasoline hydrocarbons having high antiknock value and other desirable characteristics. Isomerized hydrocarbons thus produced may, if desired, be blended all or in part with aromatic hydrocarbons initially extracted from the naphtha hydrocarbon mixture.

In accordance with the invention a hydrocarbon mixture containing aromatic and non-aromatic hydrocarbon constituents, including paraffins and naphthenes, is extracted with water or with a solvent consisting essentially of water under conditions such that aromatic hydrocarbons are removed. The remaining non-aromatic hydrocarbon mixture containing naphthenes is subjected to contact with a catalyst under conditions such that isomerization constitutes the principal reaction.

The extractive treatment with water or a solvent consisting essentially of water is advantageously effected at a temperature in the range about 400 up to 600° F. or up to the critical temperature of the lowest boiling constituent which it is desired to extract, and preferably in the range above 500° and below the critical temperature of the lowest boiling constituent to be extracted from the feed mixture. The treatment is effected under sufficient pressure to maintain the solvent substantially in the liquid phase and this pressure may range from about 1000 to 5500 pounds per square inch gauge.

As disclosed in my pending application, Serial No. 382,327, filed March 8, 1941, for Separation of aromatic hydrocarbons from hydrocarbon mixtures, water under the foregoing conditions exerts a preferential solvent action upon aromatic hydrocarbon constituents of naphtha so that aromatic constituents can be extracted from naphtha without effecting substantial removal of naphthenic and paraffinic constituents.

Moreover, under the foregoing conditions water exerts relatively low solvent action upon olefinic constituents of naphtha so that the extractive treatment may be applied to naphtha containing

olefins without effecting substantial removal of olefinic hydrocarbons.

Accordingly, the invention has to do with the removal of aromatic hydrocarbon constituents from the feed to an isomerizing reaction without effecting substantial removal of other hydrocarbon constituents desirable as components of the feed to the isomerizing reaction. It contemplates extraction of aromatics from straight-run naphtha following which the non-aromatic fraction or a portion thereof is isomerized by contact with a metallic halide type of catalyst. It also contemplates extraction of aromatics from cracked naphtha following which the non-aromatic fraction or a portion thereof is subjected to contact with a suitable conversion catalyst to effect isomerization of olefinic constituents.

Thus, in the isomerization of straight run naphtha or fractions thereof by contact with a metallic halide type of isomerization catalyst, the naphtha hydrocarbons are subjected to extraction with water or a solvent consisting essentially of water to remove aromatic constituents without effecting substantial removal of naphthenic constituents, the presence of which is desirable during the isomerization reaction of paraffin hydrocarbons with a metallic halide catalyst. It has been found that the presence of naphthenic hydrocarbons in the reaction zone substantially inhibits cracking of the hydrocarbons undergoing treatment and also substantially inhibits deterioration of the catalyst.

Aromatic hydrocarbons when present in the feed to an isomerization reaction employing a metallic halide catalyst such as aluminum chloride and hydrogen chloride appear to inhibit the isomerization reaction. Aromatics also react very readily with the metallic halide to form objectionable complex compounds with consequent deterioration of the catalyst.

Therefore, an important advantage of the invention resides in effecting removal of the aromatic constituents without effecting substantial removal of naphthenic constituents which are desirable in the feed to an isomerization process employing a metallic halide catalyst.

Olefinic hydrocarbons are also usually undesirable in an isomerization reaction employing a metallic halide catalyst since they also cause substantial catalyst deterioration. Consequently, when olefinic constituents are present it is desirable to effect their removal in addition to the removal of aromatic constituents prior to treatment with the metallic halide type catalyst.

While straight run naphtha is substantially

free from olefinic constituents, cracked naphtha on the other hand, usually contains olefinic constituents in substantial amount. Therefore, it is advantageous to subject cracked naphtha to an isomerizing treatment with a different type of catalyst wherein olefinic hydrocarbons are isomerized. In such treatment cracked naphtha is subjected to contact with a cracking type of catalyst such as activated aluminum silicate or a synthetic silica-alumina gel at a temperature in the range about 750 to 950° F. and at atmospheric pressure, or thereabouts, using a high space velocity through the catalyst so that isomerization of olefins constitutes the principal reaction. Accordingly, in this type of reaction olefinic constituents are essential components of the feed.

Thus, a further advantage of the invention resides in subjecting cracked naphtha to extractive treatment with water or a solvent consisting essentially of water so as to remove aromatic constituents and leave a naphtha mixture comprising olefins, paraffins and naphthenes which is particularly suitable as a feed to the isomerizing reaction.

The data appearing below afford a comparison of results obtainable when isomerizing a naphtha hydrocarbon such as normal pentane by contact with an active aluminum chloride catalyst in the absence of, and in the presence of, an aromatic hydrocarbon such as benzene or toluene. The data were obtained in batch liquid phase experiments carried out at a temperature of either 160° F. or 200° F. as indicated, with a reaction time of four hours. In each case powdered anhydrous aluminum chloride of about 200 mesh was charged to the reaction vessel to the extent of about 10% by weight of the total hydrocarbon feed, the reaction being promoted by the addition of a small amount of hydrogen chloride.

drous aluminum chloride of about 200 mesh was charged to the reaction vessel to the extent of 10% by weight of the normal pentane charge, the reaction being promoted by the addition of a small amount of hydrogen chloride.

	Run		
	F	G	H
Per cent hydrogen chloride, by weight of total feed hydrocarbon	0.5	0.6	0.7
Per cent cyclohexane, by weight of n-pentane	0	10	25
Composition of hydrocarbon reaction mixture by fractional distillation, per cent by weight:			
Hydrocarbons of lower molecular weight than isobutane	0.5		0
Isobutane	51.2	1.7	1.6
Normal butane	4.5		0.5
Isopentane	22.7	65.6	55.7
n-Pentane	6.1	28.7	27.8
Hydrocarbons of higher molecular weight than normal pentane	15.0	4.0	14.4
Pentane converted to isopentane and other materials, weight per cent	94.2	75.0	69.0
Weight ratio of isopentane to n-pentane converted	23	.92	.77
Appearance of used catalyst	(1)	(2)	(3)

1 Brown liquid complex.

2 Light brown gummy solid.

3 Light brown sticky solid.

As indicated, substantially better conversion yields to isopentane are realized by carrying out the reaction in the presence of the naphthene hydrocarbon. The results also reveal that cracking is substantially eliminated by effecting the reaction in the presence of the naphthene hydrocarbon. This is borne out by the fact that in runs G and H the yields of hydrocarbons of lower molecular weight than pentane are relatively small, namely, 1.7 and 2.1 respectively.

Thus the foregoing experimental data demonstrate that while aromatic hydrocarbons are un-

	Run				
	A	B	C	D	E
Temperature, ° F.	160	160	160	200	200
Aromatic added	None	Benzene	Benzene	None	Toluene
Per cent aromatic by weight of n-pentane	0	1	25	0	10.
Per cent hydrogen chloride by weight of n-pentane	0.6	1.0	0.5	1.0	1.06.
Composition of hydrocarbon reaction mixture by fractional distillation, per cent by weight:					
Hydrocarbons of lower molecular weight than isobutane	0			0	
Isobutane	47.4	0.5	0.2	49.9	1.
n-Butane	2.4			5.9	
Isopentane	25.0			22.2	
n-Pentane	7.6	98.5	99.8	6.2	93.8.
Hexanes and higher	17.6	1.0	Wet gummy	15.8	5.2.
Appearance of used catalyst	Red liquid complex	Greenish brown dry lumpy solid	Wet gummy	Brownish black mobile liquid	Thick red-black liquid

As indicated by the foregoing data, where the aromatic hydrocarbon was present the conversion reaction was practically stopped, as indicated by the fact that the hydrocarbon reaction mixture at the termination of the experiment still consisted almost entirely of normal pentane.

On the other hand the advantage of retaining naphthene hydrocarbons in the naphtha feed to an isomerization reaction is indicated by the following data, affording comparison of results obtainable when isomerizing a naphtha hydrocarbon such as pentane by contact with an active aluminum chloride catalyst in the absence, and in the presence, of a naphthene hydrocarbon such as cyclohexane. The data were also obtained in batch liquid phase experiments carried out at a temperature of about 200° F. with a reaction time of 4 hours. In each case powdered anhy-

desirable in the feed to the isomerization reaction naphthene hydrocarbons on the other hand are desirable. For this reason the pretreatment of the feed hydrocarbons with water or a solvent consisting essentially of water as contemplated by the present invention is advantageous since it permits extracting the undesired aromatic constituents from the feed while permitting the desirable naphthene constituents to remain therein.

Reference will now be made to the accompanying drawing comprising a diagram of flow for an operation involving isomerization of naphtha hydrocarbons by contact with an active metallic halide catalyst.

As indicated in the drawing straight run naphtha from a source not shown is conducted through a pipe 1 to a heater 2 wherein it is heated to a temperature in the range 400 to 600° F. and then

introduced to the lower portion of an extraction tower 3.

The extraction tower 3 is advantageously provided with a suitable inert packing material such as Raschig rings.

The naphtha flows upwardly through the extraction tower and countercurrently to a body of water maintained at the aforesaid temperature. Water is continuously introduced to the upper portion of the tower through a pipe 4 and to which reference will be made later.

As a result of the contact between water and naphtha within the extraction tower 3 formation of extract and raffinate phases occurs. The extract phase accumulates in the bottom of the tower and comprises a large proportion of water containing aromatic constituents of the naphtha dissolved therein.

This extract phase is continuously drawn off through a pipe 5 and passed through a cooling coil or heat exchanger 6 wherein it is cooled to about room temperature or to a temperature in the range about 70 to 250° F., for example.

The cooled mixture is then conducted to a separating vessel 7 wherein separation between aromatic hydrocarbons and water occurs. The separated aromatic hydrocarbons are continuously drawn off from the top of the separator 7 through a pipe 8 while the water substantially free from aromatic hydrocarbons is continuously drawn off from the bottom of the vessel 7 through a pipe 9.

The withdrawn water is advantageously conducted through a pipe 10 and forced by a pump 11 through a heater or heat exchanger 12 communicating with the previously mentioned pipe 4 through which the water is thus recycled to the top of the extraction tower. The apparatus may be arranged so as to permit recycling of the water by thermo-siphon action.

The raffinate phase accumulating in the top of the extraction tower 3 comprises a relatively small amount of water mixed with the insoluble portion of the naphtha consisting essentially of paraffinic and naphthenic hydrocarbons. This raffinate phase is continuously drawn off through a pipe 13 and conducted through a cooler or heat exchanger 14 wherein the temperature is reduced to about room temperature or in the range about 70 to 250° F.

The cooled mixture is passed to a separating vessel 15 wherein separation between raffinate hydrocarbons and water occurs. The separated water is continuously drawn off from the bottom of the vessel 15 and all or in part returned through the heater 12 and the pipe 4 to the upper portion of the extraction tower 3.

The separated raffinate hydrocarbons are drawn off from the top of the vessel 15 through a pipe 16 and conducted to a vessel 17 wherein they are subjected to further settling at the same or a lower temperature to permit settling of the remaining water. If desired the raffinate hydrocarbons may be subjected to any suitable treatment at this point such as drying to effect complete or substantially complete removal of water.

From the vessel 17 the raffinate hydrocarbons are conducted through a pipe 18 to an isomerization unit 19. In this unit the hydrocarbons are subjected to contact with a metallic halide catalyst such as aluminum chloride in the presence of a promoter such as hydrogen chloride. The temperature of reaction may be in the range of about 160 to 300° F. or higher. The reaction may be effected in either vapor or liquid phase

depending to some extent upon the boiling range of the hydrocarbons undergoing conversion and also upon the form in which the catalyst is employed.

5 Thus, in a vapor phase type of operation the vapors may be passed through a reaction zone packed with the catalyst in solid fragmentary form. For example, the catalyst may comprise a solid supporting material such as alumina impregnated with aluminum chloride.

On the other hand, where a liquid phase operation is employed the catalyst advantageously comprises aluminum chloride dissolved or suspended in a substantial body of fluid, such fluid comprising for example, aluminum chloride-hydrocarbon complex. Such an operation may be carried out in a continuous manner in a reaction zone having provision for maintaining a substantial body of reaction mixture therein with provision for continuous withdrawal of a stream of the reaction mixture and continuous recycling of at least a substantial portion of the withdrawn stream to the reaction zone so as to impart thorough agitation to the reaction mixture within the reaction zone. Such an operation permits maintaining a relatively high ratio of naphthene hydrocarbon to entering feed hydrocarbon. This ratio at the point of introduction of the fresh feed to the reaction zone advantageously ranges from 1 to as high as 1000 or more by volume.

30 That portion of the reaction mixture continuously discharged from the isomerization unit 19 is conducted through a pipe 20 to a fractionation unit 21 wherein it is subjected to fractionation. This fractionation may include separation of normally gaseous material including hydrogen halide promoter used in the isomerization reaction, segregation of isomerized hydrocarbons into one or more gasoline fractions of desired boiling range, and separation of heavier material as, for example, hydrocarbons boiling above the range of the desired gasoline fraction or fractions.

35 Provision may be made for fractionating from the reaction mixture a fraction rich in naphthenic hydrocarbons, which fraction is desired for recycling to the isomerization unit for the purpose of maintaining the desired high ratio of naphthenes to paraffins entering the isomerization unit. This high boiling naphthenic fraction may 40 comprise, for example, a fraction drawn off from the bottom of the fractionator through a pipe 22 or from the lower portion thereof through a pipe 23 and which is then passed through a pipe 24 to the isomerization unit 19.

45 55 Hydrogen chloride fractionated out of the reaction mixture may be recycled through a pipe 25 to the isomerization unit 19. Any hydrogen formed in the isomerization reaction can likewise be fractionated out of the reaction mixture and 60 may also be recycled all or in part to the isomerization reaction through the pipe 25.

65 If it is desired to carry out the isomerization reaction in the presence of extraneous low boiling gaseous hydrocarbons such as ethane, propane, butane or isobutane, provision can be made for segregating a fraction comprising these gaseous materials from the reaction mixture. For example, such fraction may be drawn off from the fractionation unit through a pipe 26 and recycled all or in part through branched pipe 27 leading to the isomerization unit 19.

70 75 The isomerized hydrocarbons or any desired fraction thereof drawn off from the fractionation unit through a pipe 28 may be passed all or in part through a branched pipe 29 to a tank 30 and

therein blended with all or a portion of the previously mentioned aromatic extract discharged from the separator 7 through pipe 8. The resulting blend may be used for the manufacture of high antiknock motor fuel.

While aluminum chloride has been specifically mentioned as an isomerization catalyst it is intended that other metallic halide catalysts may be employed such as aluminum bromide, zirconium chloride, antimony chloride, mixed metal halides such as $AlCl_2F$, AlF_3Cl , etc., or mixtures of halides such as $AlCl_3-SbCl_3$. Metallic halide may be used in fragmentary form or supported upon solid materials such as Porocel, alumina, charcoal, etc.

Suitable promoters may comprise besides hydrogen chloride, other hydrogen halides, carbon tetrachloride, alkyl chlorides, etc.

As already indicated, in addition to the advantage of effecting the isomerization reaction in the presence of naphthene hydrocarbons for the purpose of preventing cracking of the paraffins undergoing treatment and deterioration of the catalyst during the conversion, other extraneous materials may be employed in addition for still further inhibiting cracking and catalyst deterioration. These other materials may comprise normally gaseous materials such as hydrogen, hydrogen-containing gases and normally gaseous hydrocarbons or mixtures thereof.

As already mentioned the solvent employed in the extraction step may consist entirely of water or essentially of water. Thus, it is contemplated that water may contain a suitable auxiliary substance for the purpose of increasing the solubility of aromatic hydrocarbons in the solvent mixture without substantially reducing the selectivity of the mixture as between aromatic and non-aromatic constituents of the hydrocarbon mixture undergoing extraction. Suitable auxiliary substances comprise hydroxy and polyhydroxy organic compounds which are substantially completely soluble in water at least at temperatures of the order of 70 to 600° F. Dihydroxy saturated and unsaturated alcohols such as ethylene and polyethylene glycols have been found effective for this purpose. The di, tri and hexa ethylene glycols may also be used as well as the halogenated derivatives of the dihydroxy alcohols such as trimethylenechlorohydrine, glycerol b-dichlorohydrine and a-chloroglycerol.

Other organic compounds which may be used include polyolefin glycols, polyvinyl alcohols, polyhydroxyl alcohols such as glycerine, mannitol and sorbitol. Phenolic compounds such as resorcinol, phloroglucinol and pyrogallol may be used. Still other compounds include the hydroxy acids such as salicylic and lactic acids, and the aliphatic alcohols including amine and nitro derivatives thereof, such as mono, di, and tri ethanol amines and 2-nitro ethanol.

The proportion of added substance which may be employed is such that the mixture of water and secondary solvent will exert substantial solvent action upon aromatic hydrocarbons at temperatures of 200° F. and above but will exert substantially little solvent action upon aromatic hydrocarbons at ordinary temperatures, for example, from about room temperature to about 250° F. In other words, the proportion of secondary solvent and water in the solvent mixture is such that when the solution of desired aromatic hydrocarbons in the solvent is separated from the extraction zone the desired aromatic hydrocarbons can be substantially entirely separated from

the solvent merely by reducing the temperature of the solution to a temperature in the range about 70 to 250° F.

Thus, the proportion of above-mentioned hydroxy material contained in the water may range from a fraction of a per cent to 50% or more by weight of the solvent mixture and preferably will range from about 5 to 25% by weight.

Instead of using an extraction tower as illustrated in the drawing, the extraction may be effected in other types of apparatus including mixers and settlers arranged in stages.

The invention may be applied to the treatment of naphtha or to any desired fraction or fractions thereof. For example, straight run naphtha may be fractionated into light and heavy fractions; the light fraction may comprise hydrocarbons boiling up to about 200° F. and substantially free from aromatic hydrocarbons, while the heavier fraction will comprise hydrocarbons boiling above 200° F. and which will contain substantially all of the aromatic constituents present in the straight run naphtha. The heavy fraction may thus be subjected to the extractive treatment to remove aromatic constituents and thereafter isomerized. The light fraction may be separately isomerized or subjected to isomerization along with the aromatic free heavier fraction.

A substantially similar pretreatment may be applied in the case of cracked naphthas which are to be subjected to the isoforming reaction already referred to above.

Also with respect to the isoforming of cracked naphtha it is contemplated that the solvent extraction step may be controlled so as to remove substantially all or only a portion of the aromatic constituents.

In describing the type of isomerization catalyst that may be employed reference has been made to the term "fragmentary" and this term is used in a generic sense to include any form in which the solid catalyst may be employed including powder, pellets, pills, particles, granules or lumps, etc.

While it is contemplated removing substantially all of the aromatics from the feed to the isomerization reaction nevertheless it may be sufficient in some instances merely to substantially reduce the aromatic content. For example, where the isomerization reaction is to be carried out under relatively high temperatures, for example, temperatures substantially above 200° F., the retention of a small amount of aromatic material in the feed may be tolerated.

Obviously, many modifications and variations may be made in the invention as herein set forth without departing from the spirit and scope thereof, and therefore only such limitations should be imposed as are indicated in the appended claims.

I claim:

1. In the manufacture of gasoline from a naphtha hydrocarbon mixture containing aromatic and non-aromatic hydrocarbons including naphthenes and paraffins, the method which comprises subjecting the naphtha hydrocarbon mixture to treatment with a solvent consisting essentially of water at a temperature in the range above 500° F. and below the critical temperature of the lowest boiling constituent to be extracted from the naphtha mixture and under a pressure sufficient to maintain the solvent substantially in the liquid phase, such that the solvent has substantially no solvent action upon naphthenic constituents, forming an extract phase rich in aro-

matic hydrocarbons and a raffinate phase comprising non-aromatic hydrocarbons including said naphthenic constituents, separating said phases, removing solvent from the raffinate phase hydrocarbons, subjecting the solvent-free raffinate phase hydrocarbon mixture to contact with a metallic halide isomerization catalyst maintained under isomerizing conditions at a temperature in the range about 160 to 300° F. such that isomerization constitutes the principal reaction, effecting isomerization of paraffin constituents of the raffinate mixture in the presence of said naphthene constituents and removing isomerized hydrocarbons from the resulting products of reaction.

2. The method according to claim 1 in which isomerized hydrocarbons are blended with aromatic hydrocarbons obtained from the extract phase.

3. In the manufacture of gasoline from a naphtha hydrocarbon mixture containing aromatic, naphthenic and paraffinic hydrocarbons, the method which comprises subjecting the naphtha mixture to treatment with a solvent consisting essentially of water at a temperature in the range about 500 to 600° F. and under a pressure sufficient to maintain the solvent substantially in the liquid phase such that the solvent has substantially no solvent action upon naphthenic constituents of the mixture, forming an extract phase rich in aromatic hydrocarbons and a raffinate phase comprising naphthenic and paraffinic hydrocarbons, separating said phases, removing solvent from the raffinate phase mixture, subjecting the solvent free raffinate mixture to contact with a metallic halide isomerization catalyst in a reaction zone at an elevated temperature in the range about 160° F. up to about 300° F. such that isomerization constitutes the principal reaction, effecting isomerization of paraffin constituents of the mixture in the presence of said naphthene constituents, removing hydrocarbon products of reaction from the reaction zone, separating from the removed products isomerized hydrocarbons, also separating from said removed products a fraction rich in naphthene hydrocarbons and recycling at least a portion of said naphthene rich fractions to the isomerization reaction zone.

4. In the manufacture of gasoline from a naphtha hydrocarbon mixture containing aromatic and non-aromatic hydrocarbons including naphthenes and paraffins, the method which comprises

subjecting the naphtha hydrocarbon mixture to treatment with a solvent consisting essentially of water at a temperature in the range of about 500 to 600° F. and under a pressure sufficient to maintain the solvent substantially in the liquid phase such that the solvent exerts relatively low solvent action upon naphthene constituents and relatively high solvent action upon aromatic constituents, forming an extract phase rich in aromatic hydrocarbons and a raffinate phase comprising paraffin hydrocarbons and naphthene hydrocarbons, subjecting the solvent free raffinate phase hydrocarbon mixture to contact with aluminum halide isomerization catalyst in the presence of hydrogen halide in a reaction zone at a temperature in the range about 160 to 300° F. such that isomerization constitutes the principal reaction, effecting isomerization of paraffin constituents of the raffinate mixture in the presence of said naphthene constituents and removing isomerized hydrocarbons from the resulting products of reaction.

5. In the manufacture of gasoline from a naphtha hydrocarbon mixture containing aromatic and non-aromatic hydrocarbons including naphthenes and paraffins, the method which comprises subjecting the naphtha hydrocarbon mixture to treatment with a solvent consisting essentially of water at a temperature in the range of about 500 to 600° F. and under a pressure sufficient to maintain the solvent substantially in the liquid phase such that the solvent exerts relatively low solvent action upon naphthene constituents and relatively high solvent action upon aromatic constituents, forming an extract phase rich in aromatic hydrocarbons and a raffinate phase comprising paraffin hydrocarbons and naphthene hydrocarbons, subjecting the solvent free raffinate phase hydrocarbon mixture to contact with aluminum halide isomerization catalyst in the presence of hydrogen halide in a reaction zone at a temperature in the range about 160 to 300° F. such that isomerization constitutes the principal reaction, effecting isomerization of paraffin constituents of the raffinate mixture in the presence of said naphthene constituents, removing products of reaction from said zone, separating from the removed products a gaseous fraction comprising hydrogen halide and a fraction comprising isomerized hydrocarbons, and recycling said gaseous fraction at least in part to said reaction zone.

GEORGE B. ARNOLD.
